United States Patent Office

Des. 218,327
Patented Aug. 11, 1970

218,327

CABINET OR SIMILAR ARTICLE

Marino Acerbis, Seriate, Italy, assignor to Industria del Mobile Acerbis Benvenuto S.n.C., Seriate, Bergamo, Italy

Filed Mar. 10, 1969, Ser. No. 16,137

Claims priority, application Italy Sept. 9, 1968

Term of patent 7 years

Int. Cl. D6—01

U.S. Cl. D33—19

FIG. 1 is a perspective view showing two sides of the cabinet or similar article at a closed position;

FIG. 2 is a perspective view showing the other two sides of the cabinet shown in FIG. 1; and

FIG. 3 is a perspective view showing the cabinet of FIG. 1, but with the drawers and doors at an open position.

I claim:

The ornamental design for a cabinet or similar article, substantially as shown.
